UNITED STATES PATENT OFFICE.

HARRY J. SHELTON, OF UNIVERSITY CITY, MISSOURI.

GRINDER.

Application filed November 7, 1927. Serial No. 231,547.

My invention relates to certain new and useful improvements in grinders for grain, and other suitable material, the peculiarities of which will be hereinafter described 5 and claimed.

The main object of my invention is to provide a screen mounting in a grinder of the class described, that will afford ready access to the screen for changing it while 10 the grinder is running, and avoid loss of time and expenditure of power from frequent stopping. In grinding grain of various kinds, it is necessary to use a screen having perforations of a size corresponding to 15 the fineness desired. When such a grinder is used for general grist mill work, for example, a load of wheat may follow one of cob corn or other coarse material. An appropriate screen must be employed for each 20 material, and frequent changes of screen are made. Usually the grinder must be stopped to change the screen. Though the power is shut off, the heavy cylinder of discs and hammers continues to rotate for several 25 minutes—actually fifteen minutes in some cases. Again, after the change of screens has been effected, the starting torque of one and a half to twice the running amperage, uses power without accomplishing useful 30 work of grinding. I propose to shorten the time of changing screens to a minimum and avoid stopping the grinder, by the construction now to be described.

In the accompanying drawings on which 35 like reference numerals indicate corresponding parts, Fig. 1 represents a vertical central section across the shaft and casing of a grinder having my improvements in operative position applied thereto; Fig. 2, a plan 40 view of my improved screen frame with a portion of a screen thereon; Fig. 3, a detail top and end view of my inner end bar for such frame; Fig. 4, a section similar to Fig. 1, but on a reduced scale and with my 45 screen frame withdrawn from the grinder for changing the screen thereon; and Fig. 5, a vertical section on the line 5—5 of Fig. 4, showing the screen in operative position.

Referring to the drawings, the numeral 50 1 designates the shaft of a grinder of the class described, on which are mounted discs 2 having hammer rods 3 to which are pivoted hammers 4 constituting the cylinder and rotating in the direction of the arrows. 55 A casing therefor consists of lower sides 6

having at one end an opening 7 with a door 8 set against a shoulder or otherwise, and secured by a wedge bar 9 at the top, as shown in Fig. 1. The opposite end is closed by a spacer plate 10. Upper sides 11 connected by curved front and back plates 12 and 13 with grinding plate 14, form a cover preferably hinged at 15, and a feed inlet 16. A semi-circular rib 17 concentric with the shaft projects inward from each lower side, forming a shoulder to engage the top of an arcuate screen 18, supported by a corresponding frame consisting of side pieces 19, connected by rods 20 with pipe spacers, and cross bars 21 and 22 at the ends of the semi-circle. The bar 21 is preferably flush with the upper face of the side pieces and fastened to the sides by machine screws 23 or otherwise. The bar 22 adjacent the grinding plate projects inward substantially to 75 the cylindrical plane of the inner face of the screen, and has a groove on its lower side forming a lip 24 to hold the upper edge of the screen and prevent feed being wedged beneath it. The upper faces of the sides 19 are inclined or recessed outward near the bar 22, to admit the adjacent screen edge to 80 said groove. The ends of the bar are reduced to form shoulders and pass through holes in the side pieces; they are prevented 85 from turning by rivets or otherwise, while extensions, integral or otherwise, project laterally from the side pieces and form pins 90 that enter grooves 26 in the lower side of the casing and guide the inner end of the frame and screen by a sliding and pivotal engagement therewith, when the fastening devices free the screen and frame from the 95 operative position.

These fastening devices preferably consist of a spring catch at each end of the frame, automatically engaging each cross bar when in operative position and holding the screen firmly in operative position against the ribs 17, or otherwise. The rear 100 or inner catch preferably consists of a strut 27, pivoted at its lower end to the spacer plate 10 and slightly beveled at its upper end to engage the under side of the cross bar 22 with a wedge action under the pressure of a spring 28. A rod 29 is pivoted to the strut and extends through a hole in the back plate to the outside, for use as a handle to disengage the strut from the cross bar 22 as indicated by dotted lines in Fig. 1. A 110

cross pin 30 in the rod limits the inward movement of the strut under the tension of the spring, so that its end will be in the path of the bar 22 as shown in Fig. 4.

- 5 The other end bar 21 is also preferably held in operative position by an automatic catch, such as a spring 31 riveted to an angle spacer 32 of the cover, and extending down past the bar 21 where it ends in a beveled hook 33 adapted to secure this end of the frame and screen in operative position. The door 8 backs against this catch and is firmly held by the wedge bar 9 to prevent accidental disengagement of the catch.
- 15 These guiding grooves 26 are beyond and below the ribs 17, and are suitably curved as they pass from the central plane at the rear to the door opening at the front of the grinder, so as to allow the screen and frame 20 to be withdrawn from the casing as shown in Fig. 4. The screen can then be easily and safely removed from the frame and another put in place. The outer end of the frame is then raised as indicated by dotted lines in 25 Fig. 4, and a quick shove assisted by the weight of the frame, slides the pins 25 to the rear and upper end of the guiding grooves 26, where the strut 27 is snapped under the bar 22, as shown. The front end bar 21 is 30 then raised till it is engaged by the hook end 33.

The inner upper corner of the bar 22 is rounded to avoid interference with the rotating hammers under the pivotal movement 35 about the pins 25. Also the grooves 26 are preferably located so that only the upper rear ends of the grooves approach the hammers to guide the bar 22 to operative position, while the lower and front portions of 40 the grooves diverge from the hammers and guide the bar 22 outward to the door opening. The front ends of the slots 26 are preferably provided with a stop bolt 34 to prevent the pins 25 leaving the grooves when 45 the frame is drawn out as shown in Fig. 4, and thus facilitate returning it to operative position.

While I have shown and described the screen and frame as being withdrawn 50 through a door opening at the front of the grinder, the door opening may be in the rear if desired, and the screen and frame withdrawn accordingly.

I claim:

- 55 1. A grinder of the class described comprising rotary hammers, a casing having an end door and side casing grooves adjacent to the hammers, an arcuate screen and supporting frame detachably mounted in the casing adjacent to the hammers—one end 60 of said frame having side projections engaging the side casing grooves and forming a sliding pivotal engagement with the casing allowing withdrawal through the end open-

ing—and means to secure the screen and frame in operative position.

2. A grinder of the class described, comprising rotary pivoted hammers, a casing having an end door opening, a door for said opening, an arcuate screen and supporting frame detachably mounted adjacent to the hammers and one end adjacent to said door, and an interposed spring catch adapted to engage said end and backed up by the door when closed preventing disengagement until 75 opened.

3. A grinder of the class described, comprising rotary hammers, a casing having an end opening, an arcuate screen and supporting frame detachably mounted adjacent to the hammers—the inner end of the frame having a sliding pivotal engagement with the casing—a catch engaging said end in operative position and having an extension outside the casing to release the catch, and means to secure the other end of said frame in operative position.

4. A grinder of the class described, comprising rotary hammers, a casing having an end opening and inside grooves, an arcuate screen and supporting frame detachably mounted adjacent to the hammers—the inner end of the frame having lateral projections in sliding pivotal engagement with said inside grooves—the inner ends of the inside 95 grooves approaching the hammers to guide the screen and frame to operative position, and the outer ends of said grooves diverging from the hammers to facilitate its withdrawal from the casing through said end 100 opening.

5. A grinder of the class described, comprising rotary hammers, a casing having a door opening and arcuate inside grooves, an arcuate screen and supporting frame detachably mounted adjacent to the hammers—said frame having arcuate sides and end bars supporting the respective sides and ends of said screen—the inner end bar having extensions projecting through the sides into 110 the arcuate side grooves of the casing forming a sliding pivotal engagement with the casing, substantially as described.

6. A grinder of the class described, comprising rotary hammers, a cooperating grinding plate, a casing therefor, an arcuate screen and supporting frame having arcuate sides and connecting end bars—the end bar adjacent to the grinding plate having on its under side a groove forming a lip for the 120 inserted end of the screen—the inner face of the frame near said end being inclined outward to facilitate insertion of the screen in said groove.

In testimony whereof I have affixed my 125 signature.

HARRY J. SHELTON.
